UNITED STATES PATENT OFFICE.

GEORGE W. BLAIR, OF PITTSBURG, PENNSYLVANIA.

DESIGN FOR A LAMP-CHIMNEY.

SPECIFICATION forming part of Design No. 20,679, dated April 21, 1891.

Application filed March 23, 1891. Serial No. 386,139. Term of patent 7 years.

To all whom it may concern:

Be it known that I, GEORGE W. BLAIR, of Pittsburgh, in the county of Allegheny and State of Pennsylvania, have invented a new and original Design in Lamp-Chimneys, of which the following is a full, clear, and exact description, reference being had to the accompanying drawing, forming part of this specification, which shows in side elevation, partly in vertical section, a lamp-chimney embodying the design.

My invention, which relates to a design for lamp-chimneys, consists in the novel outline shape of the chimney, substantially as hereinafter described, and as shown in the accompanying drawing.

The ornamentation of the chimney does not form a feature of limitation of the invention.

The chimney, as shown in the drawing, has a portion 5, with vertical side lines, and above it a body portion 2 of larger diameter, tapering upwardly from its widest portion, and above that the chimney bulges outwardly to form an annular shoulder 3, and above the shoulder 3 the chimney contracts in diameter and is formed with a similarly-constituted annular shoulder 4, above which is the neck 6.

I claim—

The design for lamp-chimneys, substantially as herein shown and described.

In testimony whereof I have hereunto set my hand this 19th day of March, A. D. 1891.

GEO. W. BLAIR.
